UNITED STATES PATENT OFFICE.

HARRY L. HARRIS, OF NEW YORK, N. Y.

WHISK-BROOM.

SPECIFICATION forming part of Letters Patent No. 748,370, dated December 29, 1903.

Application filed August 1, 1903. Serial No. 167,915. (No model.)

To all whom it may concern:

Be it known that I, HARRY L. HARRIS, a citizen of the United States, and a resident of New York, in the county of New York and State of New York, have made certain new and useful 5 Improvements in Whisk-Brooms, of which the following is a specification.

My invention is an improvement in brooms, being in the nature of a rubbing attachment 10 for use in removing spots and the like from garments; and the invention consists in certain novel constructions and combinations of parts, as will be hereinafter described and claimed.

15 In the drawings, Figure 1 is a perspective view of my improved broom. Fig. 2 is a detail perspective view showing the several parts detached for purposes of illustration, and Fig. 3 is a detail section on about line 20 3 3 of Fig. 1.

The body A of the broom may be of ordinary construction, and it may be secured to the handle B, of wood or the like, in the usual manner by wiring, for instance, as shown in 25 the drawings. Upon this handle B is secured a pad of absorbent material. This pad, as shown, includes the core or roll D and the body or wrapper E, both made of absorbent material—such, for instance, as felt, cloth, 30 canvas, cotton goods, or other suitable fabric or absorbent material—which may be manipulated to secure the construction of pad as shown in the different views.

The core D is a roll of fabric of a diameter 35 substantially equal to that of the handle B, and it is fitted upon the end of the handle, as shown in Fig. 3.

The wrapper E has a fold E' turned in from 40 its upper end and of a width approximately one-third the width of the wrapper-sheet, so the wrapper when folded to the position shown in Fig. 2 will be doubled at its upper portion, its lower portion e being of single thickness, as shown in Figs. 2 and 3. In forming the pad 45 upon the broom-handle the roll D is placed upon the upper end of the handle or shank B, (see Fig. 3,) and the end e' of the folded wrapper is secured, it may be, by tacks e², as shown in Figs. 2 and 3, to the shank B and 50 by stitches e³ to the roll D, and the wrapper

is then wound upon the roll and shank and upon itself into the form shown in Figs. 1 and 3, and it may be secured by the external row of stitches e⁴ and by the wire C, or by either of said instrumentalities, if desired. It is 55 preferred, however, to stitch the free end of the wrapper at e⁴ and also to wrap the lower portion of the wrapper with the wire C, as thereby I secure the desired form of handle with the knob or enlargement at its outer end, 60 forming a desirable handhold and also affording ample rubbing-surface for use in removing spots and the like from garments. It will be noticed the central roll D forms a suitable center for the pad, while the doubling of the 65 upper portion of the wrapper E gives the desired enlarged form to the upper end of the pad and produces the knob-like effect desired.

In use the pad may be saturated with naphtha, gasolene, benzene, or other cleaning materials and then rubbed on grease or other spots to readily remove the same. For use in cleaning muddy garments the pad may be used dry. By combining the pad with the 75 broom I provide a convenient form of handle for the broom and also furnish an article which may be conveniently used for cleansing garments, as before described.

Having thus described my invention, what 80 I claim as new, and desire to secure by Letters Patent, is—

1. The handle or shank provided with the central roll of a diameter equal to that of the shank and fitting upon the latter, and the 85 wrapper folded upon itself at its outer edge and wound upon the roll and shank forming a handle-pad having a knob shape at its outer end substantially as set forth.

2. The combination in a broom with the 90 handle of a wrapper folded at its outer edge and wound upon and secured on the handle, the outer folded portion of the wrapper producing the knob-like form at the outer end of the pad substantially as set forth.

HARRY L. HARRIS.
